STRINGED INSTRUMENT ATTACHMENT

Filed June 28, 1928

UNITED STATES PATENT OFFICE

SZCZEPAN SIEJA, OF CHICAGO, ILLINOIS

STRINGED-INSTRUMENT ATTACHMENT

Application filed June 28, 1928. Serial No. 288,852.

The present invention relates to attachments for violins or other stringed instruments and has for its main object the provision of a device by means of which a beginner 5 may be taught the proper position for the left hand, and more particularly for the left thumb upon the violin.

A pupil has a tendency to place the thumb upon the finger board, therefore a further object of the present invention is to force the 10 pupil to hold his thumb underneath the neck of the violin and not around the same or above it.

A still further object of the present invention is the provision in combination with the 15 device indicated of physical means for indicating to the pupil various scale positions on the violin.

A still further object of the present invention 20 is the provision of a device of the character indicated provided with means for attaching the same to various sizes of the instruments.

A still further object of the present invention 25 is the provision of the attachment for the purpose stated which may be cheaply and inexpensively manufactured, and which may be preferably stamped out of a blank sheet of metal.

With the above general objects in view and others that will appear as the nature of the 30 invention is better understood, the same consists in the novel construction, combination and arrangement of parts hereinafter more fully described, illustrated in the accompanying 35 drawing and pointed out in the appended claims.

In the drawing forming a part of this application and in which like designating characters refer to corresponding parts throughout the several views,

Fig. 1 is a side elevational fragmentary view of the violin, showing the neck portion 40 thereof with the present device attached thereto;

Fig. 2 is a cross-sectional view on line 2—2 of Fig. 1 through the neck plate portion of the violin with the present device attached 45 thereto;

Fig. 3 is a cross-sectional view on line 3—3 of Fig. 1;

Fig. 4 is a cross-sectional view on line 4—4 of Fig. 1;

Fig. 5 is an elevational perspective view of 55 the present attachment; and

Fig. 6 is a cross-sectional view similar to that of Fig. 4 showing a modified attaching means for the device, whereby the same may be attached to the violin.

Referring in detail to the present drawing there is shown therein the violin body indicated by 10, having the usual neck plate 11, neck 12, finger board 13, and peg box 14, provided with conventional peg bores 15.

The invention, best shown on Fig. 5, includes side plate 16 having the upper edge flaring out as at 17 for the purpose of preventing said plate from coming in contact with the neck 12 and thus preventing said plate from scratching the neck of the violin.

Integrally formed with and positioned substantially at the right angle with said plate 16 is a plate 18 which has a curved and outwardly flaring edge 19 so that at one end said plate 18 fuses with plate 16 while the other end of said plate 18 terminates in a triangular lug 20.

Cut out from the wider end of plate 18 and upwardly bent is a lug 21 which remains substantially in parallel relation with 70 plate 16. At the other end of the device, integrally formed with said plate 16, substantially at a point where one end of said plate 18 merges with said first named plate 16 is an L-shaped bracket 22, one upright portion of which remains in substantially parallel relation with said plate 16. Said plate 16 is further provided with upwardly extending projection 23 which is on a line with 75 the bracket 22 and reaches to substantially the same height.

Plate 16 has three outwardly projecting bulges 24 of graduated size. On the inside face of plate 16 said bulges form depressions which may be easily felt by the thumb of the 80 player as the same comes in contact with said plate 16.

Thus by the size of a given depression the player will be able to ascertain by feeling alone on what scale or position his hand rests.

Plate 16 has three outwardly projecting bulges 24 of graduated size. On the inside face of plate 16 said bulges form depressions which may be easily felt by the thumb of the 85 player as the same comes in contact with said plate 16.

Thus by the size of a given depression the player will be able to ascertain by feeling alone on what scale or position his hand rests.

As is apparent one end of plate 16 and the opposite lug 21 are adapted to engage the neck plate 11, while the other end of plate 16 including projection 23 and bracket 22 are adapted to engage the inner end of peg box 14. In the operative position of the device upon the violin plate 18 will be positioned below the neck 12, while plate 16 will be disposed below said neck 12 and to one side thereof, as clearly seen on Fig. 3. In holding the violin by the left hand the thumb will rest below neck 12 and will contact with the inner face of plate 16 on the line with depressions formed by bulges 24. Portion 15 of the left hand will contact with curve 19 of plate 18, while the other four fingers of the left hand will assume the usual position upon the finger board 13.

Since peg box 14 and neck plate 11 are not of uniform thickness in all violins, a modified attaching means, illustrated on Fig. 6 is provided. Said attaching means includes a spring plate 25 riveted or in other suitable manner anchored by its lower end to a portion of bracket 22, as at 26. The upper end of said spring plate 25 carries pin 27 which passes through aperture 28, the inner end of said pin 27 being adapted to engage the adjacent face of peg box 14. By this arrangement in case the peg box is too narrow in order to permit the frictional engagement therewith of plate 16 and a portion of bracket 22, pin 27 will be adapted to frictionally engage the face of said peg box 14. A similar attaching means may be provided upon lug 21 to engage the adjacent portion of neck plate 11.

While there is described herein a preferred embodiment of the present invention, it is nevertheless to be understood that minor changes may be made therein, without departing from the spirit and scope of the invention as claimed.

What I claim as new is:

45 1. An attachment for a stringed musical instrument having a neck, neck plate and peg box, comprising a plate for embracing the lower portion of the neck and positioned below the upper surface of said neck, and means 50 associated with said plate for securing the attachment to the neck.

55 2. An attachment for a stringed musical instrument having a neck, neck plate and peg box, comprising two plates for embracing a side and bottom of said neck, and means associated with said plates for securing the attachment to the neck.

60 3. An attachment for a stringed musical instrument having a neck, neck plate and peg box, comprising a plate for embracing the lower portion of the neck and positioned below the upper surface of the neck, said plate having thumb locating indentations, and means associated with said plate for securing the attachment to the neck.

4. An attachment for a stringed musical instrument having a neck, comprising a plate for embracing the lower portion of the neck and positioned below the upper surface of the neck, a substantially triangular plate secured to said first plate, and means associated with both plates for securing the attachment to the neck. 70

5. An attachment for a stringed musical instrument having a neck, comprising a plate for embracing the lower portion of the neck and positioned below the upper surface of the neck, said plate having means associated therewith for adjusting its tension about the neck, and other means cooperating with the plate for securing it to the neck. 80

In testimony whereof I affix my signature.
